UNITED STATES PATENT OFFICE.

WILLIAM M. MARTIN AND CHARLES N. CHURCH, OF BURLINGTON, NEW JERSEY.

RECONDITIONING METAL MOLD.

Application filed September 27, 1926. Serial No. 137,965.

This invention relates to molding and has special reference to a method and apparatus for repairing cracked or checked metallic molds.

In the molding of pipe and other like articles, it is common to effect the molding by centrifugal force and in practice the molding is performed in metallic molds which may be constructed of steel, Monel metal, stellite or other metals or alloys. Such molds are subject in use to alternate heating and cooling and this sets up internal stresses which cause cracking or checking of the internal surface of the mold so that the article cast therein presents a rough exterior and is difficult and sometimes impossible to withdraw from the mold. This is due partly to the development of the cracks themselves and partly to the edges of the cracks curling upwards from the normal surface of the mold. Consequently such metallic molds have heretofore been discarded as soon as such cracking or checking became serious while the mold actually, if the cracks were closed, could be used for a much longer time.

The present invention has for its objects, among others, the provision of an improved method of treating cracked metal molds to close the cracks and also the provision of improved apparatus whereby the method may be carried in practical operation and wherein means will be provided for adjusting the device to suit molds of different internal diameters and molds having internal diameters varying at different points such as tapered molds.

In the following detailed description of this invention, we shall refer to the accompanying drawings in which:

Figure 1 is a longitudinal section, partly in elevation, showing an improved device for closing the cracks in a mold of the character described;

Figure 2 is a section on the line 2—2 of Figure 1;

Figure 3 is a diagrammatic section of a checked or cracked mold showing the characteristic condition of such mold before repairing;

Figure 4 is a view similar to Figure 3 showing diagrammatically a characteristic section through the mold after being repaired by the present method;

Figure 5 is a sectional view, partly in elevation, of an apparatus for treating molds in accordance with this invention;

Figures 6 and 7 are diagrammatic sectional views similar to Figs. 3 and 4 showing respectively a checked and a repaired mold when the checks are not very large.

In carrying out this method by which cracked or checked molds are repaired, the mold is suitably supported and the edges of the cracks are forced down to the normal surface of the mold. This causes the up-curved edges on the opposite sides of the crack to move toward each other until they contact and thus close the crack. The necessary force for this purpose may be applied in a variety of ways as by percussion or hammering, rubbing or burnishing, or rolling and, in some instances, two or more of such operations may be combined. Whatever the particular manner in which the method is carried out the effect produced is to close the cracks and smooth the surface of the mold by forcing the material at the opposite edges of each crack together and into conformity with the normal surface of the mold.

Any suitable apparatus for supporting the mold and for causing relative movement between the mold and the operating mechanism may be employed. Hence for purposes of illustration only, we have shown in Fig. 5, a mold supporting arrangement comprising a casing or housing 8 provided with rollers 9 at either end upon opposite sides upon which the mold 13 may revolve. The housing is carried at its ends upon flanged wheels 10 which rest upon track rails 11 extending along opposite sides of the housing.

The housing 8 may be formed in two longitudinal divided halves bolted together. The right-hand end is provided with an end ring member 8^a spaced away to provide an annular space to receive the gear ring 4, and secured in any suitable manner to the body of the housing as by a number of straps 8^b bolted to permit the ring member to be readily detached when a mold is to be inserted or removed. The joints between the stationary housing and the rotatable mold and the rotary sleeve 5 may be closed by means of split piston rings 5^a.

The mold is rotated by means of a suitable motor 1 mounted on the housing and provided with a pinion 2, in mesh with a gear 3, which drives the gear ring 4, splined to the rotary sleeve 5 which revolves in bearings in the end of the housing and to which the bell of the mold is fastened in any suitable manner. The housing may be moved longi-

tudinally along the track rails, while the motor is rotating the mold, by means of the hydraulic cylinder 6, having its piston rod 7 secured to the block 7^a carried by the housing.

We have devised a special rolling tool which is employed for closing the cracks in the mold and this tool consists of a sleeve through which extends a shaft 16. To one end of the sleeve 15 is pinned or otherwise secured a sleeve 17 of sufficient diameter to surround the shaft 16 in spaced relation and within this sleeve adjacent its center, is secured a collar 18 through which the shaft 16 passes. Telescopically mounted in the open end of the sleeve 17 is a short sleeve 19 through which the threaded end 20 of the shaft 16 passes. On this threaded end is screwed an adjusting nut 21 and between said nut and the sleeve 19 is a washer 22. Within the sleeve 17 between the collar 18 and sleeve 19 is a coiled compression spring 23 and a similar spring 24 is arranged on the opposite side of said collar and bears against a collar 25 pinned to the shaft 16. This arrangement permits adjustment of the shaft 16 in the sleeve 15, while, at the same time, permitting the shaft to move in either direction against the action of said springs. On the opposite or forward end of the sleeve 15 is pinned a head 26 which is splined to the shaft 16 by a key 27. The forward end of the shaft 16 is reduced and on this forward end is fixed what may be termed a movable head 28, the head 26 being a fixed head in comparison. The head 28 is held on the shaft by a nut 29 and washer 30. The adjacent ends of these heads are frusto-conical in form and on these frusto-conical ends rest the corresponding ends of rollers 31 having journals 32 mounted in the radial slots 33 of a roller cage 34. End plates 35 are held to the cage by bolts 36. The rollers can thus move in and out radially and project beyond the periphery of the cage. This rolling head is inserted in the mold for rolling the latter and the rollers 31 are adjusted to bear against the interior of the mold by proper manipulation of the nut 21, revolution in one direction moving the head 28 toward the head 26 and causing projection of the rollers and revolution of the nut in the other direction allowing the heads to separate and the rollers to move inwardly.

In Figure 3 there is diagrammatically disclosed the condition of a mold 13 under checking and it will be noted that the interior of the mold is full of radial cracks, the edges of which have sprung upwardly under the influence of the stresses set up by alternate heating and cooling. If the roller head be revolved through such a mold in proper adjustment the pressure exerted by the rollers will force these edges back to the normal surface and, due to the decrease in the curva-

ture of the metal between adjacent cracks, the edges of each crack will be brought together as shown in Figure 4, the rolling being continued until the surface is brought to its normal condition. Frequently, of course, the checks are much smaller than those shown in Fig. 3 and are more like those illustrated in Fig. 5, so that they may be closed and the inner surface may be made smooth as indicated in Fig. 7.

If there be any variations in the diameter of the mold the springs 23 and 24 will permit automatic adjustment of the rollers to compensate for such variations.

While the mold has been here shown as 80 rotating during the operation it is obvious that the mold may be stationary while the rollers are revolved, with the same result.

We claim:—

1. The method of repairing interiorly 85 cracked metallic molds which consists in applying pressure to the mold at the edges of the cracks sufficient to force the edges of each crack together.

2. The method of repairing the interior surfaces of molds having cracks therein wherein the edges of the cracked portions are curled up from the normal surface at the sides of the cracks which consists in exerting sufficient pressure on the said interior surface 95 to force the curled up portions into normal surface positions and thereby bringing the sides of the cracks together at said surface.

3. The method of repairing a tubular metallic mold having surface cracks extending 100 into its internal surface which consists in subjecting the cracked surface to a rolling operation to thereby bring the sides of the cracks together at said surface.

4. In a device for rolling the checked surface of internally checked tubular metallic molds, a sleeve, a shaft extending through said sleeve, a fixed head on one end of the sleeve, a movable head carried by the corresponding end of the shaft, said heads having opposed frusto-conical ends, rollers having frusto-conical ends resting on the frusto-conical ends of the heads, a roller cage supporting said rollers on said heads, and resiliently yieldable means to impart longitudinal movement of the shaft relative to the sleeve in either direction to thereby automatically adjust the rollers to compensate for variations in the interior wall of the mold.

5. In a device for rolling the checked surface of internally checked tubular metallic molds, a sleeve, a shaft extending through said sleeve, a fixed head on one end of the sleeve, a movable head carried by the corresponding end of the shaft, said heads having opposed frusto-conical ends, rollers having frusto-conical ends resting on the frusto-conical ends of the heads, a roller cage supporting said rollers on said heads, a second

sleeve carried by the first sleeve and spaced concentrically from the shaft, a collar fixed within the second sleeve and surrounding the shaft, a third sleeve telescopically mounted in the end of the second sleeve, an adjusting nut screwed on said shaft to force the third sleeve inwardly of the second sleeve, a coiled compression spring between the collar and third sleeve, a collar fixed to the shaft in spaced relation to the first collar 10 and on the side opposite the spring, and a second coiled compression spring between said collars.

In testimony whereof we affix our signatures.
